UNITED STATES PATENT OFFICE.

EDWARD C. SMITH, OF BROOKLYN, NEW YORK.

RAIL-SAWING MACHINE.

SPECIFICATION forming part of Letters Patent No. 367,167, dated July 26, 1887.

Application filed April 29, 1886. Serial No. 200,615. (No model.)

To all whom it may concern:

Be it known that I, EDWARD C. SMITH, a citizen of the United States, residing at Brooklyn, in the county of Kings and State of New York, have invented certain new and useful Improvements in Rail-Sawing Machines, of which the following is a specification.

My invention relates to improvements in rail-sawing machines; and the objects of my improvements are, first, to afford facilities for rocking the saw-frame, and, secondly, to provide a positive automatic movement for feeding the saw to the rail.

In the accompanying drawings, which fully illustrate the novel features of my invention, Figure 1 is a front elevation of a rail-sawing machine containing my improvements. Fig. 2 is a transverse section, taken on the line *xx* of Fig. 1; and Fig. 3 is an enlarged detail face view of the saw-carrying frame, a portion of the same being broken away to show the feeding mechanism.

Referring to the drawings, *a* is an elongated rectangular frame provided at its lower end with jaws *b* *b'*, one of which, *b'*, is so bent and shaped as to form a bed or rest for a railway bar or rail, *c*, and to which it is firmly clamped by means of the threaded bolt *d*, passing through a threaded opening in the remaining straight 30 jaw, *b*.

e is an inner frame or carriage arranged within the main frame *a*, which slides up and down between ways or guides *f*, (see Fig. 2,) formed on the side bars of the said outer frame, *a*, which guides fit into slots in the side bars of the carriage *e*.

To a shaft, *g*, projecting from the sliding carriage *e*, is pivoted the saw-carrying frame *h*, so that the latter may oscillate back and forth past the side of the frame *a*. Mounted on the same shaft, *g*, and secured thereon by nut *i*, is a triple-armed piece, *j*, the two upper arms, *j'*, of which are provided with sockets, into which are inserted lever-bars *k*, for convenience in operating the same by hand. The central downwardly-projecting arm *j''* is secured at its lower end to the saw-carrying frame *h* by means of pin *k'* and nut *l*. The lower or swinging end of the saw-carrying frame is prolonged by arms *m* *m* to form a fork within which is secured the toothed saw-blade *n*, the cutting-edge of which is the arc of a

circle concentric with the pivotal point of the frame *h*. The saw-blade is rigidly fastened at one end, and is secured at the other by a screw-bolt, *o*, projecting through the opposite arm, *m*, and carrying the threaded nut *p*, by which the saw may be tightened.

The oscillation of the saw-carrying frame *h* is effected by moving the arms *j'* alternately up and down. As the saw-blade is moved back and forth over the rail it is fed downward upon the latter by the downward movement of the carriage *e* within the frame *a*, and the movement of the carriage is governed by the threaded shaft *q*, which passes through the cross-bar *r* of said carriage *e*, and is led upward through a threaded opening in the upper part of the frame *a*, and terminates in a hand-wheel, *a'*, by which it may be rotated to raise or lower the carriage *e*.

In lieu of the crank for moving the carriage to feed the saw, I provide an automatic feed, as follows: A ratchet-wheel, *s*, is mounted on the screw-shaft *q*, and to the cross-beam *r* of the sliding carriage *e* is pivoted the inner end of an arm, *t*, having on its lower end a pawl, *w*, with a coil-spring, *v*, which pawl is made to engage the ratchet at each revolution of the shaft *q*. From the arm *t* projects a stud, *x*, and on the inner surface of the arm *j''* is secured a cross-piece, *c'*, having lugs *d'*, so that as the saw-frame *h* is moved to and fro the frame *j* is made to oscillate, causing the lugs *d'* to strike the stud *x*, moving the arm *t* back and forth, and causing the pawl to move the ratchet one step at a time, rotating the shaft *q* and lowering the carriage *e*, which carries the saw-frame. The lateral movement of the saw-frame is controlled by means of a pin, *h'*, which projects from the frame *a* and works in slot *g'*, formed in the saw-frame.

The movement of the spring-pawl, as it engages the ratchet-wheel *s*, is limited by the pin *f'* working in slot *e'*. (See Fig. 2.)

In place of the independent portion *j'* and *j''*, as hereinbefore described, for operating the saw-frame, the saw-frame itself may be constructed with projecting horizontal arms for operating it.

What I claim as new, and desire to secure by Letters Patent, is—

1. In a rail-sawing machine, the main frame, a vertically-sliding carriage, with suitable

means for moving said carriage, combined with a saw-carrying frame pivoted to the movable carriage so as to swing outside of the main frame, and provided with horizontal arms for 5 operating it, and having a slot-and-pin connection with the sliding carriage, as set forth.

2. The combination, in a rail-sawing machine, of a main frame, a sliding carriage, means for moving said carriage, a saw-frame 10 pivoted on a shaft projecting from the movable carriage, and a triple-armed frame secured to said saw-frame and shaft and provided with sockets for receiving lever-bars, as set forth.

15 3. In a rail-sawing machine, the combination of a main frame, a movable carriage mounted in said frame carrying an oscillating saw-frame, with an arm pivoted to the said

carriage and provided with a movable pawl adapted to engage with a ratchet-wheel 20 mounted on a vertical screw-shaft, and a stud arranged to contact with lugs on the saw-frame for feeding the saw to the rail, as set forth.

4. The combination, with the main frame, sliding carriage, and screw-shaft mounted in 25 said carriage, of an arm pivoted to the sliding carriage carrying a spring-actuated pawl arranged to engage a ratchet-wheel on the screw-shaft, and an oscillating saw-carrying frame provided with lugs arranged to contact with 30 a stud on said arm for operating the same, as set forth.

EDWARD C. SMITH.
